UNITED STATES PATENT OFFICE.

MARVIN CAMPBELL, OF SOUTH BEND, INDIANA.

DESIGN FOR A SNAP-HOOK.

SPECIFICATION forming part of Design No. 32,655, dated May 15, 1900.

Application filed April 18, 1900. Serial No. 13,391. Term of patent 14 years.

To all whom it may concern:

Be it known that I, MARVIN CAMPBELL, a resident of South Bend, in the county of St. Joseph and State of Indiana, have invented and produced a new and original Design for Snap-Hooks, of which the following is a specification, reference being had to the accompanying drawings, wherein—

Figure 1 is a front elevation of a snap-hook embodying my design, and Fig. 2 is a side elevation of the same.

My design relates to a snap-hook produced from spring-metal wire, and the characteristic features thereof comprise a loop or ring 1, formed by coiling the length of wire from which the snap-hook is formed at a point central of its length in such manner as to form one complete turn and to overlap the respective ends along three sides, as at 2 3, respectively, to form a loop or ring by which the snap may be attached; approximately-parallel side bars 4, formed in continuation of the respective ends of the part of the wire from which the loop 1 is formed, of equal length 25 and each bent inwardly, as at 5, at an obtuse angle to meet and intersect each other on the median line of the snap-hook, and jaw portions 7 beyond the point of intersection 6, formed into hooks 8, lying in parallel planes 30 at right angles to the plane of the main body of the hook and resting against each other at their proximate sides, as at 9, the hooks of

the respective ends being formed to open in opposite directions. As thus formed it will be seen that the device as a whole is symmetrical when viewed from any direction. The eye 10, formed by the overlapping hook portions 8, is of oblong or link form, as shown clearly in Fig. 2, and the ends of the respective hooks are constructed to terminate at 35 points intermediate of the length of said eye, as indicated at 11 12, respectively, the hook portions being of like size and configuration, so as to register with each other when viewed in side elevation. The returned end portions 40 13 of the hooks are deflected outwardly away from each other to provide a V-shaped opening 14 between them, as indicated clearly in Fig. 1, the object of this configuration being to facilitate the forcing of a metallic ring or 45 the like between the hooks, it being obvious that the ring can be fully engaged with the eye by simply turning it at right angles after it has been forced inwardly between the hook members to a point below the terminating 50 55 ends of the latter.

I claim as my new and original design—
The design for a snap-hook, substantially as herein shown and described.

MARVIN CAMPBELL.
